WILLIAM H. CLEVELAND, OF WELLINGTON, KANSAS

TRACK RAIL GAUGE

Application filed November 26, 1928. Serial No. 322,044.

The invention relates to gauges for determining the distance between the rails of a track, either in laying new track, truing up old tracks or replacing track rails.

5 Primarily the invention has for an object the provision of a device of this character which may be conveniently employed in correctly gauging the rails of railway tracks or parallel lines of rails under all conditions.

10 Further, it is an object to provide such a device which is adjustable and frictionless, a device which can be inserted in position and removed without rail friction at the place of contact.

15 Further, it is an object to provide a rail gauge with removable shims so that it may be employed in determining the gauge of the rails through curves.

Still further it is an object to provide a 20 gauge which will work freely with beaded or ragged edge rails.

Another object is to provide a gauge having hinged sections so designed and constructed as to permit ready placement and 25 removal without friction at the points of contact between gauge and rails, thereby enabling the rail to be spiked down tight while the gauge is in place; it also is an object to coordinate the parts of the hinge joint and 30 the rail-contacting end of the hinged section so that the joint can be broken without friction between rail and gauge and without appreciable wear on the gauge.

Further, it is an object to provide the 35 hinged members with a locking device of such construction as will effectively hold the sections rigidly in line while the gauge is applied.

A still further object is to so design and 40 construct the joint between the sections of the gauge as to reduce wear on the hinge pin to a minimum.

Yet another object is to so arrange the 45 essential parts of the device that old types of rigid track gauges with worn-out points, due to rail contact rendering them inoperative, may be reclaimed and made operative by attaching, with a suitable union connection to the old gauge part, a portion (the hinged 50 end including the locking device and the

track engaging section) of my apparatus, thus conserving both material and labor by retaining the major portion of the old gauge in service when desired.

Other objects will in part be obvious and 55 in part be pointed out hereinafter.

To the attainment of the aforesaid objects and ends, my invention consists in the novel details of construction and in the combination, connection and arrangement of parts, 60 hereinafter more fully described and then pointed out in the claims.

In the drawings:

Figure 1 is a plan of a portion of a railway 65 with my invention in use.

Figure 2 is a side elevation showing the gauge in the act of being placed, the rails being shown in cross section.

Figure 3 is a view similar to Figure 2, showing the device in vertical longitudinal section 70 in the applied position.

Figure 4 is a detail side elevation of the hinged rail-contacting member.

Figure 5 is a plan thereof.

Figure 6 is a cross section on the line 6—6 75 of Figure 3.

Figure 7 is a cross section on the line 7—7 of Figure 3.

Figure 8 is a detail vertical longitudinal section showing how the shuttle lock is placed 80 in position on the channelled bar.

Figure 9 is a side elevation of the gauge with a shim in place.

Figure 10 is a detail perspective view of the 85 shim.

Figure 11 is a detail elevation showing how old gauge parts may be utilized.

By referring to the accompanying drawings in which like numerals of reference indicate like parts in all of the figures, it will be seen that the gauge comprises the main bar 1 90 preferably of U-shape or channelled section. To one end of the bar 1 is secured the fork 2 which may or may not be insulated at 3 from the body as may be desired.

The fork 2 has its furcations provided with top rests 4 to lie on the head or ball of the rail and with gauge faces 5 that contact the sides of the head or ball of the rail. The gauge 100 faces 5, in my invention, are provided with

recesses 6 for the reception of the "beads" or ragged edges of the worn rails.

The main bar 1 near its other end is slotted in the top as at 7 for the passage of the foot 5 and neck of the shuttle lock, the bar at the ends of the slot being under-bevelled as at 8 and over-bevelled as at 9 to facilitate the introduction and withdrawal of the locking foot of the shuttle lock hereinafter referred to.

10 10 designates the pivot bolt for the movable or hinged rail-contacting member.

The bar 1 at its end remote from the fork 2 is provided with vertical end wall portions 11 and downwardly and backwardly inclined 15 end wall portions 12. The hinged rail contacting member 13 which lies in the channel of the bar 1 is provided with vertical wall portions 15 and inclined wall portions 16 to cooperate with the wall portions 11 and 12 respectively.

20 The outer end of the member 13 has a top rest 17 to lie on the head or ball of the rail and a gauge face 18 to engage the side of the head or ball of the rail, the face 18 having a recess 19 for the reception of beads or ragged edges of the rail.

The rail-contacting member 13 has a rear top inclined wall 20 serving as a stop to limit the hinge movement or break the joint. It 30 also has a second inclined wall 21 so as to clear the toe of the shuttle foot when the joint is broken. The shuttle lock body 22 is also of channelled section to fit over the bar 1 and it is provided with a foot 23 connected to the 35 body by a spacer block or neck 24 that operates in the slot 7. The heel 25 of the shuttle lock's foot, when the parts are assembled, lies continuously beneath the bevelled portion 9 of the bar 1 while the toe part 26 lies beneath 40 the under-bevelled part 8 of the bar 1.

45 The toe 26 has a bevelled contact face 27 on its lower surface to cooperate with the inclined wall 20, and it has a flat top face 28 to cooperate with the top wall of the bar 1 in locking the hinged rail-contacting member in its operative position.

50 It will be noted particularly by reference to Figure 8, that the shuttle lock foot 23 has a recess 29 adjacent its toe end, the purpose 55 of which is to permit the ready insertion and withdrawal of the lock from the bar 1 when the hinged rail-contacting member 13 has been detached.

55 When it is desired to use the gauge on curved track it is necessary to employ a suitable shim 30 which, according to my invention, consists of a body having a front wall 31, a bottom wall 32 and side walls 35, the latter having pin holes 34 for the reception of cotter pins 37 which pass through a pin hole 36 in the head 14 and retain the shim on the head. The shim has a bevelled edge 33 which merges with the recess 19 and enables 60 the shim's front wall to contact the side of the

70 rail head or ball beneath the bead or ragged edge (if it be an old worn rail).

In order to utilize the old track gauges that have become worn I take the old gauge and cut off the single contact end a distance sufficient to enable a new section of gauge employing the hinged member and shuttle lock to be attached to the old section. This construction is best indicated in Figure 11, by reference to which it will be seen that 39 75 designates the old section of the gauge and 40 the new section which carries my invention, the two being joined rigidly together by a suitable joint 38 as indicated.

80 From the foregoing it will be seen that I have provided a device which may be conveniently employed in correctly gauging the rails of railway tracks under all conditions and is an improvement over other track gauges now in use, inasmuch as it is adjustable and frictionless, can be used inserted in position and removed without rail friction in contact with the point. It will work freely with beaded or ragged edged rails, releasing 85 with a hinged movement (which the rigid gauges now in use fail to do). The vulnerable contact surfaces of my device are also cut on such angles that they are rendered immune from friction wear of the parts, thereby preventing wear that would eventually result in lost motion. In re-gauging rails that have done service under heavy wheel loads it has been found that there is a rolling out or a flow of metal from the top 90 of the ball or head of the rails which flows over to the inner or gauge side of the rail, developing a bead or lip projection at the top edge of the ball of the rail. This bead prevents the old rigid gauge being inserted or removed from the rails when the rails are 95 spiked to standard gauge. The recesses 6 and 19 of my gauge receive these beads. If the rails are secured to standard gauge with a rigid gauge, the rigid gauge cannot be removed without damage to the gauge (eventually rendering it inoperative). My hinged 100 gauge however operates without stress under all such conditions, leaving the rails to a standard and uniform gauge below the beaded projections.

105 Furthermore, with the old type of gauge now in common use, the points contacting the rails in constant use soon wear away by rail abrasion and become too short. This renders them worthless for the accurate gauging of the rail. With the hinge construction as per my invention there is no friction between the gauge points and the rail, as the movement to rail contact is a lateral forward movement and the release is 110 a lateral retreating or back up movement from the rail. When the hinged device is inserted and the shuttle lock is moved forward to the locked position then the gauge is rigid 115 and immovable until released by backward 120 movement.

movement of the shuttle lock. This backward movement of the shuttle lock releases the hinged point and then the gauge can be lifted to release it from the rails without friction.

5 The cap of the shuttle lock forms a protection and is placed at convenient location to be grasped and used as a hand-hold for the workmen operating the gauge.

10 My invention is also constructed so that it may be rightly adjusted to meet the varying requirements in the varying width of the gauge of the rail at fixed measurements. The standard gauge of rails for tangent track is fixed at four feet eight and one-half inches, and through track of sharp curvature the width of the gauge between the gauge side 70
15 of the rails is increased in measurements in ratio to the increased degrees of curvature.

20 This increase in width of gauge of rails on curves is provided for by so fashioning the hinged point of the gauge as to receive graduated curve shims of thickness conforming to the desired increase of gauge distance required by the degree of curvature. These 80
25 curve shims are quickly applied when required, being secured in place by the cotter pin, and can be interchanged quickly as desired, and when not desired the gauge can be restored quickly to the standard tangent 85
30 gauge by drawing the cotter pin and removing the shim.

While I have disclosed my improvements as applied to gauges of the channel or U-bar type, it is obvious that they can be applied to gauges of the tubular type if desired without departing from the scope of the invention.

From the foregoing description, taken in 40 connection with the accompanying drawings, it is thought the construction, uses and advantages of my invention will be clear to those skilled in the art, and while I have disclosed a preferred embodiment of my invention it is obvious that changes in the details 45 of construction, combination and arrangement of parts may be made without departing from the spirit of the invention and the scope of the appended claims.

50 What I claim is:

1. In a track gauge, a bar having a rail-engaging fork at one end having provision for engaging the inner side of the rail head at two places, a rail-engaging member hinged to and adjacent the other end of said bar and having provision for engaging the inner side of a rail head, and a locking device on said bar cooperating with said hinged member and said bar to releasably hold said hinged member rigidly in its operating position.

2. In a track gauge, a bar having a rigid rail-engaging fork at one end having provision for engaging the inner side of a rail head at two places; the combination with said bar of a rail-engaging member mounted

at the other end of said bar, means hinging said member to said bar with a one-way joint to break in a vertical direction when in the operative position, and a shuttle lock on said bar to engage said hinged member and releasably hold it rigidly in its operative position.

3. In a track gauge, a bar having a rigid rail-engaging fork at one end; the combination with said bar of a rail-engaging member mounted at the other end of said bar, 75 means hinging said member to said bar with a one-way joint to break in a vertical direction when in the operative position, said bar being longitudinally channelled and said member having a shank to fit in the channel of said bar and a head to abut the end of said bar, said shank having a rear top incline, and a locking device on said bar to cooperate with said incline and releasably hold said member immovable relative to the bar when said bar and head are in abutting relation.

4. In a track gauge, a bar having a rigid rail-engaging fork at one end; the combination with said bar of a rail-engaging member mounted at the other end of said bar, 80 means hinging said member to said bar with a one-way joint to break in a vertical direction when in the operative position, said bar being longitudinally channelled and said member having a shank to fit in the channel of said bar and a head to abut the end of said bar, said shank having a rear top incline, and a locking device on said bar to cooperate with said incline and releasably hold said member immovable relative to the bar when 85
90 said bar and head are in abutting relation, said locking device comprising a shuttle body fitted over said bar, a locking foot located in the channel of said bar, a neck connecting said shuttle body and said foot, said bar having a slot to permit movement of said neck, said foot having a wedge end to engage between said bar and said incline for the purposes described.

5. In a track gauge, a bar having at one end a fixed rail-engaging element, a movable rail-engaging element hingedly mounted at the other end of said bar with a one-way joint breaking in a vertical direction when in the operative position, a locking device on said bar for releasably engaging said movable element to hold the same in operative position, said rail-engaging elements having top rests, and a face for engaging the side portion of the rail heads, the latter having bead-receiving recesses.

6. In a track gauge, a bar having at one end a fixed rail-engaging element, a movable rail-engaging element hingedly mounted at the other end of said bar with a one-way joint breaking in a vertical direction when in the operative position, a locking device cooperating with said bar and said movable element, said movable element having a top rest and a face for engaging the side portion of the

rail head, and a shim fitted over said movable elements' rail-engaging face, and means for removably securing said shim in position.

7. In a track gauge, a bar having at one end a fixed rail-engaging element, a movable rail-engaging element hingedly mounted at the other end of said bar with a one-way joint breaking in a vertical direction, when in the operative position, a locking device cooperating with said bar and said movable element, said movable element having a top rest and a face for engaging the side portion of the rail head, a shim fitted over said movable elements' rail engaging face, and means for removably securing said shim in position, said rail-engaging face having a bead-receiving recess and said shim having a surface portion merging with said recess.

8. In a rail gauge, a bar having a fork at one end provided with rail-engaging elements, a rail-engaging member at the other end of said bar and having a rail-engaging element at one end thereof, means at the other end of said rail-engaging member for hinging it to said bar, said rail-engaging member's rail-engaging element comprising a head, said bar and head having complementary vertical and inclined end contact walls therebetween, said rail-engaging member having a heel, and a shuttle lock on said bar with a foot to engage said bar and said heel to lock said hinged rail-engaging member rigidly to said bar in engaging positions with said walls in contact.

9. In a rail gauge, a bar having a fork at one end provided with rail-engaging elements, a rail-engaging member at the other end of said bar and having a rail-engaging element at one end thereof, means at the other end of said rail-engaging member for hinging it to said bar, said rail-engaging member's rail-engaging element comprising a head, said bar and head having complementary vertical and inclined end contact walls therebetween, said rail-engaging member having a heel, a shuttle lock on said bar with a foot to engage said bar and said heel to lock said hinged rail-engaging member rigidly to said bar in engaging positions with said walls in contact, said bar having a slot for the insertion of said foot, said foot being of a greater length than said slot whereby when the parts are assembled said lock is retained against removal from the bar.

10. A rail gauge comprising an articulated body having at one end a two-place rail-contacting element, and at the other end a one-place rail-contacting element, means for holding said body rigid at times, said means being slidably mounted longitudinally on said body to a release position, said body when said means is in the release position being adapted to be lifted to break its joint and

simultaneously cause its rail-contacting elements to move away from the rails.

11. In a track gauge, a bar having a rail-engaging fork at one end, a rail-engaging member hinged when considered with relation to its operative position on a horizontal axis to and adjacent the other end of said bar, and a locking device on said bar co-operating with said hinged member and said bar to releasably hold said hinged member rigidly in its operating position, said rail-engaging fork and said rail engaging member each having elements for engaging both the top of the rail and the inner face of the head of the rail.

12. In a track gauge, an articulated bar including a channelled section and a second section pivoted thereto, a wedge lock slidably supported on one section and releasably engaging the other section for holding the sections of the bar in rigid alignment.

13. In a track gauge, an articulated bar including a channelled section having a slot, a lock mounted on the channelled section and having a portion projecting through said slot and cooperating with the other section of the articulated bar for releasably holding the sections of the bar in rigid alignment.

14. In a track gauge, an articulated bar including two sections hinged together, one of said sections having a bifurcated end to contact a rail at two places, the other section having its end single to contact an opposite rail at a single place, the hinge axis of said sections lying parallel to the plane containing the bifurcations of the first mentioned section, and a locking device slidably mounted on one section for releasably engaging the other section of the articulated bar to hold the sections of the bar in rigid alignment.
